UNITED STATES PATENT OFFICE.

EMIL FRANCIS SWAN, OF PELHAM MANOR, NEW YORK.

CAN TOP.

Application filed September 13, 1924. Serial No. 737,588.

To all whom it may concern:

Be it known that I, EMIL F. SWAN, a citizen of the United States, and a resident of Pelham Manor, in the county of West-
5 chester and State of New York, have invented a new and Improved Can Top, of which the following is a full, clear, and exact description.

This invention relates to container tops
10 and more particularly to an improved closure for cans and the like, an object of the invention being to provide a closure which is designed to be readily removable, which perfectly seals the can airtight, and
15 which constitutes a transparent portion or window through which the contents of the can are displayed.

A further object is to provide a closure of this character which can be manufactured
20 and sold at a reasonably low price, which will be extremely ornamental and attractive in appearance, and which will most efficiently perform the functions for which it is intended.

With these and other objects in view, the invention consists in certain novel features of construction and combinations and arrangements of parts which will be more fully hereinafter described and pointed out
30 in the claims.

In the accompanying drawings—

Figure 1 is a perspective view illustrating my improved device;

Figure 2 is a view, partly in longitudinal section, on the line 2—2 of Figure 1.

1 represents a can or receptacle which may be made of any desired shape and any desired size and which is provided with a top 2 having a circular depending annular flange 3, forming a central opening through which the contents of the can can be viewed. This flange 3 at its point of juncture with the top 2 is curved or rounded as shown at 3', and the flange has an inward taper of the
45 desired degree throughout its length.

The closure for the can comprises a sheet 4 of flexible transparent material such as celluloid and the like, and a clamping ring 5 which functions to hold the sheet 4 in position and perfectly seal the can. The ring 5 has a vertical or longitudinal intermediate portion 6 of substantially the same taper as the flange 3, and at the upper end of this portion 6 an outwardly projecting annular flange 7 is provided having a turned over or rolled edge 8.

The ring 5 at its lower portion is made with an inwardly projecting annular normally horizontal flange 9 which at its point of juncture with the portion 6 of ring 5 is 60 curved or rounded as shown at 10.

It is to be understood that the flexible sheet 4 may be shaped to conform to the exterior of the ring closure member 5 so as to prevent wrinkling or crinkling of the
65 sheet when in operation.

To assemble the parts, the flexible sheet 4 is positioned against the outer face of the ring member 5 and then while the parts are thus assembled they are inserted within the flange 3 and forced downwardly until the parts frictionally bind and the upper edge 2 or extremity of sheet 4 lies against the top 2 and is concealed under the turned over edge
75 8 of the ring member 5.

The sheet 4 therefore functions not only as a window but as a close-fitting gasket which seals the can airtight. Furthermore, this sheet while acting as a perfect binder 80 will permit the closure to be manually and readily removed by inserting the finger nails or a tool under the flange 7 and prying the ring 5 upwardly.

With a device of this kind I am enabled to pack goods of various kinds within the can and have them seen clearly from the outside so as to make an attractive display and yet provide a closure which is airtight so as to preserve the goods.

Various slight changes and alterations 90 might be made in the general form of the parts described without departing from my invention, and hence I do not limit myself to the precise details set forth but consider myself at liberty to make such slight changes 95 and alterations as fairly fall within the spirit and scope of the appended claims.

I claim:

1. The combination with a receptacle having an opening, a tapering flange constituting the wall of the opening, a closure constituting a ring, and a flexible transparent sheet fitting the outer face of the ring, said sheet and ring adapted to be forced within the flange and said ring having a taper corresponding to the taper of the flange and clamping the flexible sheet between the flange and the tapered portion of the ring, this clamping means constituting the sole securing means for the transparent sheet.

2. The combination of a receptacle, a top on the receptacle and a tapering inclined

inwardly projecting flange constituting a portion of the top and also constituting the wall of a circular opening in the top, of a closure constituting a ring, and a flexible 5 transparent sheet, said ring having a taper corresponding to the taper of the flange, an annular flange on the ring having a turned over outer edge, an inwardly projecting annular flange on the ring, and said

sheet conforming in shape to the outer face 10 of the ring, acting as a gasket between the ring and the flange and having its edges concealed back of the turned over edge of the ring flange said tapered flange and the tapered portion of the ring constituting 15 clamping means and the sole securing means of the transparent material to the can.

EMIL FRANCIS SWAN.
